CONTAINER TREATING MACHINE

John M. Hothersall, Brooklyn, N. Y., and August E. Almgren, Hillside, N. J., assignors to American Can Company, New York, N. Y., a corporation of New Jersey

Application November 5, 1937, Serial No. 173,050

8 Claims. (Cl. 226—129)

The present invention relates to a container or can treating machine and has particular reference to devices for preparing a closed empty can having an attached closure element so that it will be in condition for subsequent filling, such preparatory steps including proper positioning and feeding of a can, dating the same, then opening its closure element and when in correct open position delivering it for subsequent filling or other desired operation.

An object of the present invention is the provision of a can treating machine for preparing a closed but empty milk can or the like for subsequent filling by individually feeding the empty cans (which are closed by attached closure elements) from a magazine or other source of supply, passing each can from its horizontal magazine position into upright position and dating each can by stamping the desired insignia on a suitable part thereof and then opening the can by hinging its attached closure element into open filling position, all of the operations being correlated to produce the desired results, provision being made for arresting a given operation if the can is not in proper position at its various stages and finally delivering only the properly conditioned opened cans which have been made available for the subsequent filling step, all defective cans being removed from the normal course and separated from these conditioned cans.

Another object of the invention is the provision of such a can treating machine adapted to open an empty fibre milk can or the like which is in closed or sealed condition when received within the machine, the various operations through which the can passes while in the machine automatically preparing it for immediate filling and insuring that only those cans which have been fully conditioned will be passed on to a suitable can filling machine or other desired mechanism.

Numerous other objects and advantages of the invention will be apparent as it is better understood from the following description, which, taken in connection with the accompanying drawings, discloses a preferred embodiment thereof.

Referring to the drawings:

Figure 1 is a top plan view, with parts broken away, of a can treating machine embodying the instant invention, the view also showing a portion of a can filling machine;

Fig. 2 is a fragmentary top plan view of parts

of the machine adjacent the can magazine, the view also showing cans being operated on;

Fig. 3 is a longitudinal section taken substantially along the broken line 3—3 in Fig. 1;

Fig. 4 is a transverse section taken substantially along the broken line 4—4 in Fig. 3;

Fig. 5 is a transverse section of the upper portion of the machine, the section being taken substantially along the line 5—5 in Fig. 1;

Fig. 7 is a longitudinal section taken substantially along the line 7—7 in Fig. 1, parts being broken away;

Fig. 8 is a fragmentary sectional detail of certain parts illustrated in Fig. 7, the detail showing these parts in a different position;

Fig. 9 is a transverse section taken substantially along the broken line 9—9 in Fig. 1 with parts broken away;

Figs. 10, 11 and 12 are enlarged fragmentary sectional details of the machine as viewed along a line 10—10 in Fig. 9 and showing the machine parts in different positions, Figs. 10 and 11 also showing a can being operated on;

Figs. 13, 14 and 15 are horizontal sections taken substantially along the broken lines 13—13, 14—14, 15—15, respectively, in Figs. 10, 11 and 12;

Fig. 16 is a vertical section taken substantially along the line 16—16 in Fig. 15;

Fig. 17 is an enlarged fragmentary top plan view of a can carrying tab lifting device, the view being turned through 180 degrees from that

shown in Fig. 1 and also showing a can in place in the device;

Figs. 18, 19 and 20 are longitudinal sections taken substantially along the line 18—18 in Fig. 17, the sections showing the various parts

in different positions relative to the upper end of a can, portions of the can in Figs. 19 and 20 being broken back and shown in section;

Figs. 21 and 22 are sectional views of the upper end of a can showing its tab being lifted, the views being taken substantially along the line 21—21 in Fig. 17;

Fig. 23 is a longitudinal section taken substantially along the line 23—23 in Fig. 1, with parts broken away;

Fig. 24 is a sectional detail taken substantially along a line 24—24 in Fig. 23;

Fig. 25 is a fragmentary horizontal section taken substantially along the line 25—25 in Fig. 3;

Fig. 26 is an enlarged transverse vertical sec-

tion of a tab marking portion of the machine, the view being taken substantially along the broken line 26—26 in Fig. 1, with parts broken away, a can also being shown in place in the machine;

Figs. 27 and 28 are sectional details of the tab marker as viewed substantially along the respective lines 27—27, 28—28 in Fig. 26, Fig. 27 also showing cans being operated upon;

Figs. 29 and 30 are sectional details of the tab marker taken substantially along the respective lines 29—29, 30—30 in Fig. 26, Fig. 30 also showing a can in place in the machine;

Fig. 31 is an enlarged perspective view of a part of the tab marker;

Fig. 32 is an enlarged fragmentary plan view of a can closure element lifting portion of the machine showing cans being operated upon;

Figs. 33, 34 and 35 are sectional views, Figs. 33 and 35 being taken substantially along the lines 33—33, 35—35, respectively, in Fig. 32, while Fig. 34 is taken substantially along a line 34—34 in Fig. 33, the upper portion of a can being shown in place in all of these views and shown in section in Figs. 34 and 35;

Fig. 36 is an enlarged fragmentary top plan view of a can closure element detector portion of the machine as viewed substantially along the line 36—36 in Fig. 3, the view also showing cans being operated upon;

Fig. 37 is an enlarged fragmentary section of a can detector unit being taken substantially along the line 37—37 in Fig. 1, and showing in place the upper portion of a can in section;

Fig. 38 is a view similar to Fig. 37 showing the movable parts in a different position; and

Figs. 39 and 40 are sectional details being respectively viewed substantially along the lines 39—39, 40—40 in Fig. 36.

An exemplary form of can which is adapted to be treated and prepared for filling in the machine illustrated in the drawings is fully disclosed in United States Patent Number 2,085,979, issued to John M. Hothersall on July 6, 1937. Such a can is herein indicated by the letter *b*. The can is preferably made of fibre and is provided with fibre top and bottom end members. The top end member is formed with a filling and dispensing opening *c* which is disposed at one corner of the can. This opening is adapted to be subsequently closed and sealed, after the can is filled, by a flap or closure element *d* which is hingedly secured to the top end member.

The closure element is provided with a plug section *e* formed to fit into and fill the opening *c* when the closure element is in can closing position. This closure element is formed integrally with a can lifting or carrying tab *f* the whole being secured by a staple *g* to the top end member of the can. The staple is disposed between the closure element and the tab so that they may be independently hinged upwardly.

The cans *b* to be treated in the machine have preferably been sterilized and coated interiorly and exteriorly with a suitable liquid proof, air impervious coating. The filling and dispensing opening *c* has also been closed hermetically by the closure element *d* and the can is in a sterile condition. The carrying tab *f* lies flat against the top end member.

The cans *b* as received in the machine for treatment are horizontally disposed one above the other in a vertical stack within a magazine A (Figs. 1, 7, 8 and 9). A can detecting instrumentality B (Figs. 1, 5, 9 to 16, inclusive) is dis-

posed adjacent the bottom of the magazine and functions to ascertain the fully seated position on the magazine bottom of the lowermost can. When a can is in such a position that detecting

instrumentality unlocks a can feeding device C (Figs. 1, 7, 8, 9, 13, 14, 15 and 16) which moves the lowermost can from the magazine and places it into a can setting-up member D (see also Figs. 6 and 23). Here the can is rotated into an up-right or vertical position with its top end up.

An auxiliary feeding device E (Figs. 1 and 9) thereupon removes the upright can from the setting-up member D and positions it in the path of travel of a can pusher F (Figs. 1, 2, 5, 17 and 22, inclusive) which is located adjacent a tab raising element G. The pusher advances the can past the tab raising element and places it into a rotatable turret H (Fig. 1). This movement past the tab raising element effects a raising or hinging of the tab *f* of the can so that it assumes an inclined position relative to the can end member instead of lying flat against it.

The can is now carried intermittently by the turret H through a circular path of travel. During this travel the raised tab *f* is engaged by a marking mechanism J (Figs. 1, 5, 26 to 31, inclusive) and dated. The can is advanced into another position where the closure element *d* is lifted by a closure element lifting device and suction cup K (Figs. 1, 32 to 35, inclusive). This opens or uncovers the filling opening *c*. The opened closure element is now held opened while the can is further advanced to a closure element detector and can throw-out mechanism L (Figs. 1, 37 to 40, inclusive). This detector and throw-out mechanism operates in the following manner.

If the closure element is in full open position so that the filling opening *c* is fully uncovered, the can is passed on to a transfer device M which removes it from the can treating machine and places it into a filling machine N (Fig. 1). The filling machine forms no part of the instant invention and therefore will be only briefly mentioned. However, if the closure element of the can is incorrectly positioned and the filling opening *c* is not fully uncovered the can is thrown out or discarded and is not passed into the filling machine.

The can magazine A (Figs. 1, 7, 8 and 9) is of rectangular cross-section just large enough to accommodate the can *b* as it rests in horizontal position, i. e., on one of its sides. This magazine is formed on the top of a cover plate section 51 of a main frame housing 52 carried on a machine base 53 (see also Fig. 3). The magazine is provided with a bottom plate 54 and also a pair of oppositely, laterally disposed outlet openings 55 which are formed in the side wall sections of the magazine adjacent its bottom plate.

Cans are brought into the magazine A by any suitable means from a suitable source of supply. The cans fall toward the bottom of the magazine and stack up on top of each other. The lowermost can of the stack when in proper position for feeding from the magazine is supported on the bottom plate 54 and is in alignment with the outlet openings 55.

The cans are fed from the magazine A in time with the other moving parts of the machine and it is therefore a desideratum that the lowermost can in the stack be in alignment with the magazine outlet openings 55 at feeding time so that a jam will not occur. It is for the purpose of pre-

venting such a jam that the can detector instrumentalities B are located adjacent the bottom of the magazine.

The can detector instrumentalities B include a hollow elongated head 58 which is formed on one end of a horizontal rod 59 (see also Fig. 5) carried in a pair of bearings 61 on the frame cover plate section 51. The rod is reciprocated toward and away from the magazine in time with the other moving parts of the machine by a cam actuated lever 63 which is mounted on a pivot pin 64 carried in a bearing 65. The bearing depends from the frame cover plate section 51.

The upper end of the lever 63 extends up through an opening 66 in the cover plate section and operates in a slot 67 formed in the rod 59. This connection prevents the rod from turning in its bearings. The lower end of the lever carries a cam roller 68 which operates in a cam groove 69 of a compound cam 71. The compound cam is mounted on a horizontal cam shaft 72 journaled in bearings 73 formed in the frame housing 52.

Cam shaft 72 is rotated continuously by a bevel gear 75 carried thereon. The gear meshes with a driving bevel gear 76 which is mounted on a drive shaft 77 (see also Fig. 3) carried in a bearing 78 formed in the frame housing 62 and in a bearing 79 formed in an end plate 80 which is bolted over an open end of the housing 52. The drive shaft is rotated in any suitable manner, as for example, by an endless belt 81. This belt may be driven by an electric motor 82 (Fig. 1) mounted on an extension of the machine base 53. The belt preferably takes over a suitable slip clutch 83 mounted on the drive shaft 77. It is through this driving means that the detector head 58 is periodically moved toward the magazine A.

The detector head 58 (Fig. 10) is provided at one end with a boss 85 which carries a movable detector pin 86. The detector pin projects into a hole 87 which is formed in the adjacent end wall section of the magazine A and which is located just above the magazine bottom plate 54.

When the detector head 58 moves toward the magazine A the detector pin 86 moves with it. If there are no cans in the magazine or if the lowermost can in a stack is not fully seated on the magazine bottom plate and in alignment with the magazine outlet openings 55 when the detector head moves forward, the detector pin 86 will extend into the space where the can should be as shown in Fig. 12, the pin remaining stationary in its boss 85.

If, however, a can is in alignment with the magazine outlet openings 55 the pin 86 will engage against the can end when the head moves forward and the pin will be shifted in its boss 85 to the position of Fig. 11. This shifting of the pin actuates a bell crank lever 88 which operates locking devices associated with the can feeding device C and which permits the feeding device to remove the lowermost can from the magazine.

The bell crank lever 88 is carried in the detector head 58 and is mounted on a pivot pin 89 secured in the head. The outer end of one arm of the lever extends through an opening 95 formed in the boss 85 and operates in a slot 96 in the detector pin 86. The arm of the lever is backed up by a plunger 97 and a spring 98 which are retained in a bore 99 formed in the end of

the head rod 59. This construction insures movement of the bell crank lever with the shifting movement of the detector pin 86 and also moves the pin through the bell crank lever.

The other arm of the bell crank lever 88 extends at right angles to the first mentioned arm and carries at its outer end a long pin 101 and a short pin 102. These pins are adapted to set and release a feed locking pawl 104 and a holding pawl 105 which are closely associated with the can feeding device C.

The pawls 104, 105 are mounted, as best shown in Fig. 13, on pivot studs 106 carried in a can feeding head 107 which is superimposed over a continuously reciprocated slide 108 of the feeding device C. The head 107 and slide 108 are locked together by the pawls only at a time when a can is to be removed from the magazine, otherwise the head remains inactive while the slide continues to reciprocate.

The holding pawl 105 is formed with a depending finger 101 which extends down adjacent the short pin 102 of the detector lever 88. The pawl is further formed with a hook 102 which when normally engaged over a lug 103 on the locking pawl 104 holds the latter in locking position. The pawls are normally maintained in this interlocked relation by a plunger 105 and a spring 106 which are disposed in a bore 107 in the feeding head 107. The lower end of the locking pawl 104 is provided with a projection 108 which when in locking position extends down into a locking recess 109 of the feed slide 108.

The feed slide 108 is carried in slideways 113 formed in the main frame housing 52 which are at right angles to the longitudinal center line of the magazine A and in line with its outlet openings 55. The slide is retained in the slideways by plates 115 one of which is provided with a clearance notch 116 for the locking pawl projection 108 when the latter is in its normal or non-locking position. The feeding head 107 is supported on the plates 115 and is retained in position by guide rails 117.

The feed slide 108 is reciprocated by a link 111 (see Figs. 7 and 9) one end of which connects with a lug 112 depending from the slide. The other end of the link connects with an arm 113 which is mounted on a horizontal shaft 114 carried in bearings 115 formed inside the frame housing 52. The shaft also carries an arm 116 having a cam roller 117 which operates in a suitable cam groove formed in a cam 118 mounted on the continuously rotating cam shaft 72. Through this medium the feed slide 108 is continuously reciprocated toward and away from the magazine A.

When the bell crank lever 88 of the detector instrumentalities B is rocked (as shown in Fig. 11) by the shifting of the detector pin 86, brought about by a properly positioned can in the magazine A, the long pin 101 on the end of the bell crank lever arm is moved first into alignment with the locking pawl 104. The pin 101 under movement of the head 58 thereupon moves the locking pawl forward so that its lower projection 108 engages into the recess 109 of the feed slide 108 as shown in Fig. 14. The pawl is held in this position by the holding pawl 105 as hereinbefore described. The feed head 107 and slide 108 are thus locked together and on the next feeding stroke of the slide, the head and the slide will move together in unison.

The moving feed head 107 passes into the outlet openings 55 of the magazine and pushes the

lowermost can of the stack forward and out of the magazine. This feeding action will be repeated and will continue as long as cans in the magazine are properly arranged so that successive lowermost cans fall into position in alignment with the outlet openings 55 as each preceding lowermost can is removed. Just so long the feed head 117 and slide 118 will remain locked together and the cans will be fed from the magazine in succession, each stroke of the slide delivering one can.

When a can does not fall all the way down in the magazine or when the magazine becomes empty, there is nothing to engage the detector pin 86 so it remains stationary in its boss 85 and is not pushed back when the detector head 58 moves forward. The bell crank lever 88 moves outwardly into the position of Fig. 10 each time the detector head moves back from its can engaged position of Fig. 11. This movement of the bell crank lever shifts its long pin 111 out of alignment with the locking pawl 114 and moves the short pin 112 into alignment with the finger 121 of the holding pawl 115. Accordingly, on the next forward movement of the detector head, the holding pawl is struck by the short pin and is tilted as shown in Fig. 15. This releases the locking pawl 114. In point of time this occurs just prior to the beginning of the forward stroke of the feed slide 118.

It will be understood that if during any cycle the pin 86 does not strike a can on the forward stroke of the detector head 58 (Fig. 12) the bell crank lever will not move on its pivot but will be held out by the spring pressed plunger 97. In this case it is the short pin 112 that is ready for work.

The projection 128 of the locking pawl 114 thus snaps out of the locking recess 131 of the slide 118 and enters the clearance notch 136. This unlocks the feed head 117 from the slide 118 and upon the forward stroke of the slide the head will remain stationary while the slide moves forward alone. Hence a can which may be improperly positioned in the magazine, as for example, one which is partially in alignment with the outlet openings 55 will be saved from being crushed and a jam in the machine is avoided.

As hereinbefore mentioned, a can *b* fed from the magazine A is pushed into the can setting-up member D (Figs. 1, 5, 6, 7, 9 and 23) which is located adjacent the magazine and is rotatable intermittently. The setting-up member is formed with arms 150 (Fig. 6) disposed at right angles after the fashion of a swastika and forming a star wheel. These arms set off spaced pockets 151 which are adapted to be brought successively into register with the opening 55 of the magazine A for receiving a can.

The member D is mounted on one end of a horizontal shaft 153 (Fig. 23) carried in a long bearing 154 formed on the cover plate section 51 of the main frame housing 52. The opposite end of the shaft carries a bevel gear 155. Gear 155 meshes with a bevel gear 156 mounted on the upper end of an inclined shaft 157 carried in a bearing 158 formed on a bracket 159 which is bolted to the inside bottom wall section of the main frame housing 52.

At its lower end the inclined shaft 157 carries a Geneva disc 161 having a plurality of spaced rollers 162 secured thereto. These rollers are successively engaged by a cam track 163 (see also Figs. 24 and 25) of a Geneva cam 164 carried on the continuously rotating main cam shaft 72. 70

When a can *b* is pushed horizontally from the magazine A, it is received in a pocket 151 of the then stationary setting-up member D. The cam track 163 of the continuously rotating Geneva cam 164 thereupon engages a roller 162 of the Geneva disc 161 and thereby rotates the machine parts connected therewith through a partial rotation and moves the setting-up member D through a step rotation. This action carries the pocketed can from its horizontal position into an upright position with its top uppermost, as shown in Figs. 5 and 9. During this setting-up of the can it is guided along its sides and top by a curved guide member 165 which is bolted to the side of the magazine A.

The upright can *b*, still in the setting-up member D, is now in front of the auxiliary feeding device E (Figs. 1 and 9) and before the setting-up member D makes its next partial turn, the feeding device E pushes the can out of its pocket 151 and free of the member D. The auxiliary feeding device E comprises a vertical pad 171 having a boss 172 mounted on a horizontal rod 173 carried in an arm 174 which is secured to the top of the continuously reciprocating feed slide 118. Lock-nuts 175 threaded onto the rod hold the latter in position in the arm 174 and at the same time provide a medium for adjusting the pad 171 relative to the upright can *b*.

Thus as the feed slide 118 moves forward for removing the lowermost can from the magazine A, it also carries the pad 171 of the auxiliary feeding device E forward and pushes the upright can *b* out of the setting-up member D as described above. The pushed-out can is received on a table portion 177 (Figs. 2 and 5) carried in the cover plate 51. Continued movement of the auxiliary feeding device E pushes the can across the table 177 toward the can pusher F and the tab raising element G (Fig. 1) hereinbefore mentioned.

The tab raising element G (Figs. 1, 2, 5, 17 to 22, inclusive) is located directly opposite the moving can *b* and is supported on a pivot pin 181 carried in lugs 182 formed on an upright stop plate 183 of the table 177. A free end 185 of the element is formed with a wedge shaped blade 186. The opposite end of the element carries a long rod 187 and the outer end of this rod is held under tension by a spring 188. This is the normally raised position, as best shown in Fig. 18.

The rod 187 rests against the outer end of a double acting spring barrel 191 comprising a small barrel 192 fitting within a large barrel 193 and confining a compression spring 194 between and within them. The spring 194 is a little heavier and stronger than the spring 188. The large barrel 193 is disposed in a bore 195 formed in a boss 196 on the stop plate 183 and is retained against displacement from the bore by a pin 197 secured in the boss. One end of the pin extends into a slot 198 formed in the large barrel.

The small barrel extends in beyond the face of the stop plate 183 and is retained against displacement from the large barrel by a pin 201. Pin 201 is secured in the large barrel and operates in a slot 202 formed in the small barrel. This construction permits independent sliding movement of the barrels and uses only the one spring common to both.

A can moving toward the tab raising element G under the action of the auxiliary feed device E engages against the protruding end of the small

barrel 192 and pushes the double spring barrel 191 outwardly in its bore 195 and hence swings the rod 161 outwardly against the pull of its tension spring 188. This action rocks the tab raising element G on its pivot pin 181 and brings its wedge shaped blade 186 down on top of the can end in a position adjacent the can carrying tab f as best shown in Figs. 17 and 19. The large barrel 193 is thereupon blocked against further movement and the small barrel 192 slides into it compressing the spring 194 as the can continues to advance into the position of Fig. 20.

This advancement of the can terminates when it strikes the stop plate 183. The can is now directly in front of the can pusher F as best shown in Fig. 2 and is momentarily held in this position by the auxiliary feeding device E. It is the can pusher F which next operates to further advance the can.

The can pusher F (Figs. 1, 2, 5, 17 and 23) is mounted in a guideway 205 in the cover plate section 51 and reciprocates transversely of the machine. The pusher is propelled by a pair of links 206 which connect the pusher with the upper end of an arm 207 (Figs. 5 and 23) mounted on a rocker shaft 208 carried in a bracket 209 depending from the cover plate 51. The lower end of another arm 211 also mounted on the rocker shaft carries a cam roller 212 which operates in a cam track 213 formed in the compound cam 71 on the shaft 72.

Thus on the forward stroke of the can pusher F it engages the can b still frictionally held against the stop plate 183 and pushes it forward this being transversely of the machine and at right angles to its previous movement. The can is guided by and slides between the stop plate 183 and the plate 171 of the auxiliary feeding device E. During this transverse advancement of the can the wedge shaped blade 186 of the tab raising element G still seated against the top end member of the can, digs under the outer edge of the can carrying tab f and lifts it into an inclined position, as best shown in Fig. 22.

Continued forward movement of the can pusher F delivers the can into a positioned turret pocket 221 (Fig. 1). There are a plurality of such pockets formed in the intermittently rotatable turret H hereinbefore mentioned. This turret is disposed adjacent the forward stroke end of travel of the can pusher F and comprises spaced upper and lower turret discs 223 formed integrally with a central hub 224 (see also Figs. 3, 5 and 26).

The turret hub 224 is secured on a vertical turret shaft 225 which is carried at its upper end in a bearing 226 (Fig. 1) formed in a bracket portion 227 in the top wall section of the cover plate 51 and at its lower end in a bearing 228 formed in a bottom wall section 229 of the cover plate 51. The lower end of the turret shaft extends below the bearing 228 and carries a Geneva disc 231 having a plurality of spaced cam rollers 232 secured thereto.

The rollers 232 (see also Fig. 25) are arranged in a circle adjacent the periphery of the disc and are successively engaged by a cam track 233 of a Geneva cam 234 mounted on the continuously rotating drive shaft 71. There is one cam roller 232 for each pocket 221 of the turret H so that as the rotating Geneva cam 234 engages a cam roller the turret shaft 225 is revolved through a partial rotation. This brings

75 a pocket into alignment with the can pusher F so that a can may be received therein.

80 A can received in a pocket of the turret is carried along a circular path of travel through several operating stations as hereinbefore mentioned. During this travel of the can it is supported on the table 171 (see Fig. 5) and is retained in its pocket by a curved guide rail 236 which is secured to the table 171. The extended end of the table is bolted to a flange 237 (see Fig. 26) which is formed on the turret shaft bearing 228.

85 The first step rotation of the turret H brings the can b into alignment with the marking mechanism J. The marking mechanism includes a movable hollow arm 241 (Figs. 5, 26, 27, 28, 29 and 30) which is formed on a short hollow shaft or stem 242 (Fig. 29) carried in a pair of vertical spaced bearings 243 (see also Fig. 26) of a bracket 244 bolted to the cover plate 51 adjacent the path of travel of the can. The free end of the arm 241 is formed with a stationary wedge shaped jaw 245 having a smooth inclined face 246. This end of the arm also carries a movable marking jaw 247 (see also Fig. 31) which is disposed directly over the stationary jaw 245 and is mounted on a pivot stud 248 threaded into the arm.

90 The lower face of the marking jaw 247 is inclined for cooperation with the stationary jaw 245 and also carries suitable embossed characters 249 formed thereon. In the present instance this embossment preferably indicates a day of the week. The jaw is made readily detachable so that other jaws carrying other characters, such as other days of the week, may be easily placed in the marker. This provides a means of marking the can with the day of the week on which it was handled although any other notation may be used.

95 The upper or movable jaw 247 is normally held separated from the lower or stationary jaw 245 by a compression spring 251 which surrounds the pin 252 carried in lugs 253, 254 formed on the sides of the respective jaws.

100 The jaws 245, 247 are also preferably heated. For this purpose steam is circulated through the hollow arm 241 and the resulting heat is imparted to the jaws by radiation and conduction. The steam is first introduced into the arm shaft upper bearing 243 (Fig. 29) which is divided into a steam receiving chamber 256 and a steam discharge chamber 257. These chambers are set off by bearing partition elements 258. The steam enters the receiving chamber 256 by way of an inlet pipe 259 (see also Fig. 26) which is threaded into a cap 261 bolted on top of the bearing 243. This steam pipe leads from any suitable source of supply.

105 Steam passing into the receiving chamber 256 circulates through a bore 262 in the stem shaft 242, through the hollow arm 241 and returns through a bore 263 also formed in the arm shaft. The end of the bore 263 is plugged and return steam escapes into the discharge chamber 257 through a hole 264 formed in the side of the shaft adjacent the closed end of the bore 263.

110 From the discharge chamber 257 the steam is exhausted to any suitable place of discharge by way of a plurality of holes 265 (Fig. 28) formed in the discharge chamber partition. These holes communicate with a clearance space 266 formed in the bearing 243. Steam from this space escapes by way of a hole 267 formed

in the side of the bearing and an outlet pipe 268 which is threaded into the hole.

The steam heated arm 241 is periodically rocked on the stem shaft 242 as an axis to bring the marking jaw 247 and its cooperating stationary jaw 245 into can marking position. This is effected by an arm 271 (Figs. 1, 5, 26, 28 and 29) which is keyed to the stem shaft and which is disposed between the spaced bearings 243. A set screw 272 threaded into this arm engages against the shaft and thus retains it in its bearings.

The arm 271 is connected by a link 274 (Figs. 1, 3 and 26) to a similar arm 275 mounted on the upper end of a vertical shaft 276 carried in bearings 277 formed in the cover plate 51. On its lower end the shaft carries an arm 278 having a cam roller 279 which operates in a cam groove 281 of a multiple groove barrel cam 282 mounted on the continuously rotating drive shaft 71.

As a can *b* in its pocket 221 of the intermittently rotated turret *H* comes into position under the marking mechanism *J* the steam heated arm 241 swings from its normal position (shown in dotted lines in Fig. 27) into the full line position shown in that figure. This swinging movement of the arm is brought about by the cam 282 and the normally separated jaws 245, 247 carried on the arm pass on either side of the raised tab *f* of the can, the lower or stationary jaw 245 reaching a position under the tab, while the upper or marking jaw is positioned above the tab. While the jaws are positioned the upper jaw is forced down against the tab and the heated embossment 249 on the jaw face is impressed deeply therein. The lower jaw 245 acts as an anvil and supports the tab while under this pressure.

This embossing action is brought about by a toggle device which includes a pressure head 285 (Figs. 26 and 30). The head slides in the lower portion of a vertical guide 286 formed as a part of the bracket 244. A pressure regulator member 287 is disposed in the upper portion of the guide. This member is formed with a stem 288 which extends up through the top of the guide and is provided with lock nuts 289 for yieldably holding the latter in place. A compression spring 291 is interposed between the member and the top of the guide.

The pressure head 285 and the regulator member 287 are each provided with a pivot pin 293 and these effect a connection with a pair of toggle links 294. The inner ends of the links are pivotally joined with each other and with the inner end of a rod 295 (see also Figs. 1, 3 and 5). The opposite end of the rod is secured to an arm 296 mounted on a vertical shaft 297. At its lower end the shaft 297 carries an arm 298 having a cam roller 299 which operates in a cam groove 301 of the multiple cam 282. Hence at the proper time the toggle device is actuated effecting a forcing of the pressure head 285 down against the marking jaw 247 and exerting the required embossing pressure on the tab *f*.

During the marking operation the can *b* is held firmly in its turret pocket 221 by an angular clamping plate 305 (Figs. 26, 27 and 30) which is swung into position against a corner of the can just prior to the marking operation and which is again swung out of the way at the completion of the marking operation. This clamping plate is formed on the free end of a lever 306 which is carried on a depending stud

307 secured in a boss 308 depending from the top wall section of the cover plate 51. Lever 306 is also connected by a link 309 to a lever arm 311 secured on the vertical shaft 276. Thus as the shaft 276 is rocked to shift the steam heated arm 241 into place it also swings the clamping plate 305 into place.

The marking operation is followed by the lifting of the can closure element *d* to uncover its filling opening *c*. This is effected by the can closure element lifting device *K* (Figs. 1, 3, 25, 32 to 35, inclusive) which is located adjacent the marking mechanism *J*. The can closure element lifting device *K* includes a suction cup 315 formed on an arm extension 316 of a curved rack 317. This rack has movement in a vertical plane and is thus located transversely of the path of travel of the can *b*. The sides of the rack are formed with laterally projecting ridges 318 which slide in curved guide ways 319. One of these guide ways is formed on a bracket 321 which is bolted to the top of the cover plate 51. The other guide way is bolted to the side of the bracket.

The curved rack 317 is actuated by a pinion 325 keyed to a short shaft 326 carried in a bearing 327 formed in the bracket 321 and also in a bearing 328 formed in a plate 329 bolted to the side of the bracket as best shown in Fig. 34. The shaft also carries a second pinion 331 which meshes with a straight or actuating rack 332 slidably retained in a groove 333 cut in the plate 329.

The straight rack 332 (Fig. 1) is connected by a link 335 to a lever arm 336 mounted on the upper end of a vertical shaft 337 carried in bearings 338 formed in the cover plate 51. At its lower end the shaft carries an arm 339 having a cam roller 341 which operates in a cam track 342 of the continuously rotating cam 282. Through the movement of these parts the curved rack 317 slides in its guide ways and swings the suction cup 315 into and out of operative position relative to the positioned can *b*.

When the can *b* is first brought to rest for the closure opening operation, the suction cup 315 is in the normal position of Fig. 33. The curved rack 317 immediately slides in a counter-clockwise direction and the suction cup 315 is carried into the dotted line position of Fig. 33 and in full line position of Fig. 35 in which position it is in engagement with the can closure element *d*. A vacuum is then drawn on the suction cup.

Vacuumizing of the suction cup 315 may be effected by any suitable means the drawings showing for this purpose a vacuum pump 345 (Fig. 3). Such a pump comprises a piston 346 which is reciprocated within a cylinder 347. The piston is actuated by an eccentric 348 keyed to the continuously rotating drive shaft 71 (see also Fig. 4), being operated by connection with an eccentric strap 349. The cylinder is connected by a flexible hose 350 to a valve block 351, the hose having communication with a bore 352 formed in the block. The bore also communicates with the interior of a flexible tube 354 which connects with the interior of the suction cup 315 (see Fig. 35).

The valve block 351 houses a slide valve pin 358 one end of which slides in a recess 359 containing a compression spring 361. The spring exerts an outward pressure on the slide pin. Intermediate its length the slide valve pin is supported by a collar 362 which slidably fits within

the bore 352. This collar moves adjacent the valve end of the tube 354 and serves as a plunger for opening and cutting off communication between the suction cup and the vacuum pump.

The outer end of the slide valve extends beyond the end of the valve block and is provided with a head 364. The spring 361 holds this head against the upper end of a lever 365 mounted on a pivot pin 366 secured in the housing end plate 50. The lower end of the lever carries a cam roller 367 which operates against the periphery of an edge cam 368 mounted on the drive shaft 11.

When the suction cup 315 has reached its position on top of the closure element *d* of the can *b*, the cam 368 allows the upper end of the lever 365 to be moved away from the valve block 351 under the action of the valve spring 361 which pushes the slide valve outwardly. This shifts the slide collar 362 to the right of the valve end of the tube 354 (as viewed in Fig. 4) and hence opens communication between the tube and the valve bore 352. The pump 345 thereupon draws out the air and creates a vacuum within the cup 315.

While this vacuum condition continues within the suction cup, the curved rack 317 slides in a clockwise direction (as viewed in Fig. 33) and the suction cup thereupon rocks back into its normal position. This raises the can closure element *d* into an upright position (Fig. 33) and uncovers its filling opening *c*. The vacuum is maintained on the suction cup 315 and holds the closure element in its upright position until a holding arm 371 (Figs. 32 and 33) is swung into position in front of the closure element to prevent its closing. The vacuum is then broken.

Breaking of the vacuum is effected by a further rotation of the cam 368 which rocks the lever 365 inwardly and thereby pushes the slide valve 358 so that its collar 362 is shifted to the left of the valve end of the tube 354 as viewed in Fig. 4. The interior of the tube 354 and the suction cup 315 are thereby brought into communication with the atmosphere entering the then open end of the valve bore 352. Hence the suction cup releases its hold on the can closure element *d* and the latter is held up solely by the holding arm 371 which will now be described.

The closure element holding arm 371 is mounted on a vertical shaft 372 (Figs. 1, 3, 25, 26 and 32) carried in bearings 373 formed in the cover plate 51. At its lower end the shaft carries a lever arm 374 having a cam roller 375 which operates in a cam groove 376 formed in the multiple cam 282.

With the can closure element *d* still held in upright position by the holding arm 371, the rotating turret *H* advances the can through another step toward the closure element detecting devices *L*. As soon as the can begins to move, the closure element *d* slips from the holding arm 371 and, while still in an upright position, passes along a stationary curved guide rail 378 (Figs. 1, 32, 33 and 35) which is bolted to the bottom of the bracket 227 of the cover plate 51 top wall section. The holding arm 371 thereupon swings back to its normal out-of-the-way position and the guide rail continues its holding function during the remainder of the travel of the can through the machine.

The closure element detector and can throw-out mechanism *L* (Figs. 1, 3, 25, 37 to 40 inclusive) hereinbefore mentioned includes a detector pin 381 which is carried in a boss 382 of a hollow

detector arm 383 mounted on top of a vertically movable detector shaft 384. This shaft is carried in a vertically disposed rocker sleeve 386 the lower end of which rocks in a bearing 387 formed in the cover plate 51.

The detector shaft 384 is restrained against rotation in the rocker sleeve 386 by a vertical key 391 (Fig. 37) which is secured to the arm 383 and which slides in a groove 392 cut in a lug 393 formed on top of the cover plate 51. The detector shaft is periodically raised and lowered within the rocker sleeve 386 by a bell crank lever 395 (Figs. 3 and 25) which is mounted on a pivot pin 396 carried in a bracket 397 formed as an integral part of the inside of the machine housing 52. One arm of the bell crank lever is forked and carries trunnions which operate in a groove 398 of a collar 399 which is threaded into the lower end of the detector shaft.

The other arm of the bell crank lever 395 carries a roller 402 which operates in a slot 403 formed in a horizontal slide bar 404. The bar slides in bearings 405 formed in a bracket 406 disposed inside and as a part of the machine housing 52 and is actuated by a cam roller 407 carried on the bar. The cam roller operates in a cam groove 408 of a cam face 409 which is mounted on a short shaft 411 carried in a bearing 412 of the bracket 406. The short shaft carries a bevel gear 413 which meshes with the bevel gear 76 on the drive shaft 77.

The rocker sleeve 386 is periodically rocked around the vertically movable detector shaft 384 by a lever 415 (Figs. 3 and 25) carried on its lower end. Lever 415 carries a cam roller 416 which operates in a cam groove 417 of a barrel cam 418 mounted on the drive shaft 77.

At its upper end the rocker sleeve 386 extends through a sleeve bushing 421 (Figs. 3, 37 and 38). This sleeve bushing is formed with an enlarged head 422 which is carried in a bearing 423 formed in the cover plate 51. This construction provides for support of the sleeve bushing and prevents its sliding down. The sleeve bushing head 422 is recessed as at 424 for the reception of a head 425 of the rocker sleeve. This construction of rocker sleeve head insures support of the rocker sleeve and all parts carried thereby and at the same time allows for relative rotation of these parts.

At its lower end the sleeve bushing 421 is keyed to a can guide hub 427 which carries a pair of integral short can guide segments 428 (Figs. 1 and 3) normally aligned with the end of the can guide rail 236. These short segments fill a gap 429 between the end of the guide rail 236 and a continuing guide rail 431. A bell crank 435 (Figs. 36 and 40, inclusive) is located inside of the detector arm 383 and is carried on a pivot pin 436. The outer end of one leg of the crank extends through an opening 437 in the boss 382 and operates in a slot 438 formed in the detector pin 381.

The outer end of the other leg of the bell crank extends into a slot 441 of a curved plate cam 442 having on its lower surface an inclined cam groove 443. This cam 442 is mounted on a pivot pin 445 carried in a boss 446 formed on top of the cover plate 51. A spring barrel 447 (Fig. 36) carried in a boss 448 also formed on the cover plate 51 pushes against a finger extension 449 of the plate cam 442 and thereby normally holds the opposite end of the cam against a stop lug 451 (see also Fig. 39). This lug is also formed on the top of the cover plate 51 and carries a

guide 452 which prevents vertical displacement of the slotted end of the cam.

The plate cam 442 normally bears down on a lug 455 of a tiltable yoke 456 surrounding a central collar 457 formed on the rocker sleeve head 425. The yoke is provided with trunnions 458 which are mounted in the collar. A compression spring 461 retained in recesses formed in the yoke and in the head 425 of the rocker sleeve 386 forces the lug 455 upwardly against the plate cam 442.

Diametrically opposite the yoke lug 455, the yoke is provided with a finger 462 which when the yoke is tilted, rests in a radial notch 463 formed in the top of the sleeve bushing head 422. When the finger 462 is in this notch 463 the sleeve bushing 421 is directly connected with the rocker sleeve 386 and both sleeve and bushing rock as a single unit. The effect on the can b will now be explained.

When the can being operated on reaches its position adjacent the closure element detector and can throw-out mechanism L comes to rest directly under the detector pin 381. The detector shaft 384 immediately moves down carrying with it the detector arm 383 and parts secured thereto including the detector pin. The detecting operation follows.

If the closure element d of the positioned can is in normally opened position so that the can filling opening c is fully uncovered, the descending detector pin 381 passes into the can through the filling opening as shown in dotted lines in Fig. 37. The detector pin, the bell crank 435 and the plate cam 442 therefore remain unmoved and in their normal positions relative to the descending detector arm 383. Hence the sleeve bushing 421 remains disconnected from the rocker sleeve and when the latter makes its oscillation the can guide segments remain stationary, that is, in their normal can guide positions. Thus upon the following step rotation of the turret H, the detected can advances further along its circular path of travel, being guided by the rail 236, guide segments 428 and rail 431.

If the closure element d of the can is in other than a properly opened position, as by failure of the suction cup device K to raise the closure element and uncover the can filling opening c, the descending detector pin strikes against the closure element (Fig. 38) and its downward movement is arrested. Continuing descent of the detector arm 383 effects a rocking movement of the bell crank 435. This rocking movement shifts the plate cam 442 outwardly and releases the yoke lug 455. Hence the yoke compression spring 461 rocks the yoke in a clockwise direction as viewed in Fig. 37 and presses its finger 462 into the notch 463 of the sleeve bushing head 422. This locks the sleeve bushing 421 with the rocker sleeve 386 on which the yoke is carried, this being the position of Fig. 38.

Thus as the rocker sleeve 386 rotates through the forward portion of its oscillation it also turns the sleeve bushing with it. While this oscillation takes place, the detector shaft moves up carrying with it the detector arm, the bell crank and the detector pin. The weight of the detector pin is sufficient to shift it and the bell crank back into their normal positions. The plate cam 442 being released moves back into its normal position.

Turning of the sleeve bushing 421 shifts the can guide segments 428 into the path of travel of the can as shown in full lines in Fig. 36.

Hence on the next step rotation of the turret H the advancing can engages against the guide segments 428 and is swept out of its turret pocket 221, Fig. 36 showing a can entirely free of the pocket. The removed can passes through the gap 429 adjacent the end of the can guide 236 and falls down a chute 465 (Figs. 1 and 36) into a discard bin 466 secured to the side of the machine housing 52.

10 After discarding the can the rocker sleeve 386 rocks back to its normal position and carries the guide segments back into alignment with the can guide 236 as shown in dotted lines in Fig. 36. On this return rocking movement of the rocker sleeve the lug 455 of the yoke 456 rides into the cam groove 443 of the plate cam 442 and follows along the incline of the groove. This depresses the lug and tilts the yoke back into its normal position (as shown in Fig. 37) withdrawing the 15 yoke finger 462 from the notch 463 of the sleeve bushing 421. The sleeve bushing is thereby unlocked from the rocker sleeve. This completes the throw-out cycle.

20 On successive step rotations of the turret H the can is advanced through a plurality of idle stations and thence brought into position adjacent the transfer device M (Figs. 1, 5, 25 and 26). This transfer device includes a pair of upper and lower arms 471, 472 which are disposed respectively above and below the turret H. Upper arm 471 is mounted on the lower end of a short pin 473 held in a bearing 474 formed on the bracket 227 of the cover plate 51. The lower arm 472 is mounted on the upper end of a pin 475 which is concentric with the pin 473 and which is carried in a bearing 476 formed in the table portion 171 of the cover plate 51.

25 The outer ends of the arms 471, 472 are formed with extended hubs 477 which are connected by a tie rod 478 which construction insures movement of the arms in unison. A can transfer arm 479 is an integral part of each of these hubs. These transfer arms project inwardly at an angle to the arms 471, 472. It is these transfer arms which effect the transfer of the can when the same are oscillated in unison with the arms 471 and 472.

30 The arms 471, 472 and 479 are moved by a lever arm 481 which is carried on the lower arm pin 475. A link 482 connects the lever arm 481 with a lever 483 which is mounted on a short vertical shaft 484 carried in a bearing 485 formed in the lower wall section 229 of the cover plate 51.

35 Shaft 484 (Figs. 5, 25 and 26) also carries an arm 486 which is connected by a link 487 to the outer end of a lever 488 mounted on a pivot pin 489 carried in a bearing 491. The bearing depends from the top wall section of the cover plate 51. The inner end of the lever 488 carries a cam roller 492 which operates in a cam groove 493 formed in the compound cam 71 mounted on the continuously rotating cam shaft 72.

40 When the advanced can b comes to rest adjacent the transfer device M, the transfer arm 479 moves in behind and engages the can and pushes it out of its pocket 221 of the turret H. The ends of the can guide rail 431, the closure element holding guide rail 378 and a similar curved guide rail 494 bolted on top of the cover plate 51 are shaped for guiding the can from its pocket while holding its closure element d in upright position during the transfer.

45 The removed can b may be then disposed of in any desired manner. To indicate that it is still under control while being delivered Fig. 1

indicates the can being pushed forward into a pocket 485 of a rotating turret 496 forming a part of the filling or other can handling machine N. The can may be retained in the filler turret pocket by the curved guide rail 494 or in any other manner.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for treating sealed containers having a filling opening and an attached closure element, the combination of feeding devices for advancing containers along a predetermined path of travel, a closure element lifting device for raising the container closure elements to uncover the filling openings, means for holding the closure elements in raised position, a device for detecting advanced containers having their filling openings in other than a fully open condition, and a throw-out mechanism operable by said detecting device for discarding improperly opened containers.

2. In a machine for treating sealed containers having a filling opening and an attached closure element, the combination of feeding devices for advancing containers along a predetermined path of travel, a closure element lifting device for raising the container closure elements to uncover the filling openings, means for holding the closure elements in raised position, a device for detecting advanced containers having their filling openings in other than a fully open condition, a throw-out mechanism operable by said detecting device for discarding improperly opened containers, and a transfer device adjacent said feeding devices for removing properly opened containers from said feeding devices for further treatment.

3. In a machine for treating sealed containers having hingedly attached closure elements, the combination of feeding devices for advancing containers along a predetermined path of travel, a suction cup located adjacent the path of travel of the containers, means for creating a vacuum in said suction cup, valve means for opening communication between said suction cup and said vacuum means and also between said suction cup and the atmosphere, devices for first rotating said suction cup into engagement with the closure element on the sealed containers, and second, for rotating it in the reverse direction for hinging outwardly the closure element into open non-sealing position relative to the container, said valve means operating to draw suction on the cup when it first engages said closure element and to maintain the suction on said cup while it is moving in its reverse direction, means for detecting advanced containers having their closure elements in other than fully open position, and means actuated by said detecting means for ejecting such improperly opened containers from the machine.

4. In a machine for treating sealed containers having hingedly mounted closure elements thereon normally disposed in container closing and sealing position, the combination of feeding devices for advancing the sealed containers, a closure element lifting device disposed adjacent said feeding devices for successively hinging out-

wardly the closure elements of containers from container sealing position to facilitate further treatment of said containers, means for holding said closure elements in non-sealing outwardly hinged position during such further treatment and after said lifting device is released from a said closure element, means for detecting advanced containers having their closure elements in other than fully open position, and means actuated by said detecting means for ejecting such improperly opened containers from the machine.

5. In a machine for treating sealed containers having hingedly mounted closure elements thereon normally disposed in container closing and sealing position, the combination of feeding devices for advancing the sealed containers, a closure element lifting device for successively hinging outwardly the closure elements of containers from container sealing position to facilitate further treatment of said containers, means for holding said closure elements in non-sealing outwardly hinged position during such further treatment and after said lifting device is released from a said closure element, means for detecting advanced containers having their closure elements in other than fully open position, means actuated by said detecting means for ejecting such improperly opened containers from the machine, and a transfer device adjacent said ejecting means for removing properly opened containers from said feeding devices for further treatment.

6. In a machine for treating sealed containers having hingedly mounted closure elements thereon normally disposed in container sealing position, the combination of feeding devices including a rotatable turret for advancing the sealed containers, a suction operated closure element lifting device disposed adjacent said turret for successively hinging outwardly the closure elements of said containers from sealing position to facilitate further treatment of said containers, means for holding said closure elements in non-sealing outwardly hinged position during such further treatment and after said lifting device is released from a said closure element, means for detecting advanced containers having their closure elements in other than fully open position, and means actuated by said detecting means for ejecting such improperly opened containers from the machine.

7. In a machine for treating containers having hingedly mounted closure elements thereon normally disposed in container closing and sealing position, the combination of a magazine for holding such containers, feeding devices for advancing containers successively from said magazine along a predetermined path of travel, said feeding devices including means disposed adjacent said magazine for detecting the presence of properly positioned containers therein and for holding said feeding devices from operation when a container to be fed is improperly positioned, to prevent subsequent jamming of the machine due to presence therein of improperly positioned and fed containers, and a closure element lifting device cooperating with said feeding devices for successively engaging only containers which have been properly positioned and advanced by said feeding devices, said lifting device engaging and hinging outwardly the closure elements of containers so properly advanced by said feeding devices to permit further operation thereon.

8. In a machine for treating containers having hingedly mounted closure elements thereon normally disposed in container closing and sealing

position, the combination of a magazine for holding such containers, feeding devices for advancing containers successively from said magazine along a predetermined path of travel, said feeding means including means disposed adjacent said magazine for detecting the presence of properly positioned containers therein and for holding said feeding devices from operation when a container to be fed is improperly positioned, to prevent subsequent jamming of the machine due to presence therein of improperly positioned and fed containers, a closure element lifting device cooperating with said feeding devices for succes-

5 sively engaging only containers which have been properly positioned and advanced by said feeding devices, said lifting device engaging and hinging outwardly the closure elements of containers so properly advanced by said feeding devices to facilitate further treatment thereof, means for detecting advanced containers having their closure elements in other than fully open position, and means actuated by said latter mentioned detecting means for ejecting such partially opened containers from the machine.
